UNITED STATES PATENT OFFICE.

FRED M. YOUNG, OF RACINE, WISCONSIN, ASSIGNOR TO PERFEX CORPORATION, OF RACINE, WISCONSIN, A CORPORATION OF WISCONSIN.

RADIATOR.

Application filed September 17, 1926. Serial No. 136,094.

This invention relates to radiator constructions for the cooling systems of internal combustion engines, the object of the invention being to effect increased efficiency of the radiator by means of a peculiar fin structure which operates to increase the rate of heat transfer from the water to the air passing through the radiator.

This object of the invention is attained by means of the arrangement illustrated in the accompanying drawings, which show a radiator core provided with spaced superimposed fins inclined downwardly from front to rear, transversely slotted, and so formed adjacent 10 said slots as to provide downwardly bulging and forwardly facing scoop shaped channels for directing jets of air upward through the slots. The aim of this construction is to divide the air stream into a great 15 number of angularly directed jets, crossing the main stream and impinging against adjacent fin surfaces in order to cause the air to rapidly take up heat from the radiator and to avoid the usual effect of large quantities 20 of air passing through the radiator without coming into contact with the heat radiating surfaces. A further aim is to provide in the fin structure a large number of fin 25 sharp or cut edges which are believed to materially increase the rate of transfer of heat from the fins to the passing air current.

In the accompanying drawings Fig. 1 is a fragmentary front elevation of a sectional radiator core of the general type shown and 30 described in my Sectional radiator Patent No. 1,606,204, issued November 9, 1926, a portion of one section being shown in section to better show the interior construction.

Fig. 2 is a perspective top plan view of a 35 portion of a fin plate.

Fig. 3 is a perspective bottom plan view of the same.

Fig. 4 is a sectional side elevation of a section header and the adjacent portion of the 40 core.

Fig. 5 is a top plan detail of a fin plate.

Fig. 6 is an enlarged section taken on the 45 line 6—6 of Fig. 5.

Fig. 7 is an enlarged section taken on the line 7—7 of Fig. 5.

50

Fig. 8 is a section on line 8—8 of Fig. 1.

55

The radiator structure illustrated in the drawings comprises vertically extending core sections which are individually and detachably secured by bolts 3 to the upper and lower tanks of the radiator and preferably also connected together by bolts 6 extending through lugs or flanges 4 on the side edges of core sections.

The feature of the invention to which this application for patent is directed is the fin plate as illustrated in Figures 2 and 3 and in Figures 5 to 7. This is an extremely thin sheet 10 preferably of bronze or copper having its front edge folded backwardly upon 60 itself or otherwise reinforced for strength and good appearance, thus insuring that the fin-sheet will present a straight line at the front of the radiator. This sheet is uniformly apertured to receive the water tubes 8 and is also provided with uniformly spaced transverse slots 13, as shown in Fig. 2. At one 65 side of each slot 13 the fin is depressed by suitable dies to provide scoop shaped deflectors 13'. These deflectors serve to direct and 70 permit some of the air passing through the radiator to be deflected through the slots and projected against the next adjacent fin plate. In this way the air currents through 75 the radiator are to a great extent divided and caused to brush against or wipe over the heat dissipating surfaces. Since the heat is carried away by convection it is desirable to cause the maximum possible wiping action of the air on the heat dissipating surfaces of 80 the radiator. The efficiency of this particular fin structure is greatly increased by having the fin plates closely spaced and inclined 85 downwardly from front to rear, as indicated in Fig. 4. These scoop shaped depressions 90 in the fins may either face the incoming air, as indicated in Fig. 4, or the reverse.

The usual water tubes 8 which may be in single or multiple banks, are shown connecting the upper and lower headers 9 of each 95 core section and pass through apertures 11

in the fin plates 10 to which the tubes are soldered at the flanges 12.

I claim:

5 A radiator fin structure comprising a metallic sheet apertured to receive water tubes and transversely slotted at points between the water tube apertures and having the slotted portions offset to form closed bottom

scoops adjacent the slots, each scoop being open at the slot end, whereby some of the 10 air passing along said sheet is most efficiently directed through said sheet.

Signed at Racine this 25th day of August, 1926.

FRED M. YOUNG.
